(57) **CLAIM**

An ornamental design for a burner control panel interface, as shown and described.

DESCRIPTION

FIG. 1 is a front perspective view of a first embodiment of a burner control panel interface showing our new design; FIG. 2 is a front elevation view of a second embodiment thereof;

FIG. 3 is a cross sectional view taken along line 3—3 in FIGS. 1, 4 and 6 thereof;

FIG. 4 is a front perspective view of a third embodiment thereof;

FIG. 5 is a front elevation view of a fourth embodiment thereof; and

FIG. 6 is a front elevation view of a fifth embodiment thereof.

The broken lines showing of the rear portion of the control box and the indicia on the panel are for illustrative purposes only and form no part of the claimed design. The broken line circumscribing the plane of the control panel defines the bounds of the claimed design and forms no part thereof.
